METHOD AND APPARATUS FOR
HEATING TRAINSDavid Sanborn Neuhart, 9024 Jones, Omaha, Nebr.
Filed Mar. 1, 1963, Ser. No. 262,080
5 Claims. (Cl. 237—12.4)

This invention relates to a method and apparatus for supplying auxiliary heating steam to the heating system of railroad trains. In recent years, it has become the practice to operate longer passenger trains. It is not unusual under present standards to run trains having as many as twenty-five cars.

To meet the increased demand for steam, it has been conventional practice to provide additional steam generators located at the head end of the train. Except under extreme weather conditions, this expedient has been proven to be satisfactory. However, under conditions of extreme cold, it has been found that it is impossible to heat the rear cars of a long passenger train adequately. The addition of still more steam generating equipment at the head end of the train is not an answer to the problem, since the volume of steam generated by the equipment cannot be distributed to the cars through the existing steam lines.

It has also been proposed to locate auxiliary steam generating equipment in other parts of the train, either at the rear end or an intermediate location. This proposal has not proved satisfactory because the condensate traps are inadequate to handle the large volume of condensate which accumulates at the point where the auxiliary steam flow meets the steam flow from the head end of the train. This point of intersection of the two steam flows is reasonably constant in location and is the point of maximum condensate accumulation. It will be apparent that neither of these proposals is an answer to the problem, since each would require that the existing equipment be extensively modified in order to accommodate the increased steam flow or the increased amount of condensate. Neither of these solutions is economically acceptable.

According to the present invention, auxiliary heating steam, at a lower pressure than head end steam pressure, is supplied to the train from an intermediate location or from the rear end of the train by an intermittently operable steam generator. This steam generator's operation is controlled in response to the pressure existing in the steam line where the auxiliary generator is to be located. The auxiliary steam generating equipment is completely self-contained and operates independently of the head end steam generating equipment. The auxiliary steam generator is normally inactive, but, when the pressure in the steam lines falls below a first predetermined value, its operation is commenced. Operation will continue until the pressure has risen above a second predetermined value and thereafter maintained above said first value for a predetermined time interval.

In the preferred embodiment of the invention, the auxiliary steam generator includes an internal combustion engine which drives an electric generator which in turn supplies electric power to operate a motor-driven compressor and a motor-driven fuel pump which supply fuel and air to the burners of the auxiliary steam generator. When the pressure at the location of the auxiliary steam generator falls to a first predetermined value, automatic controls start the auxiliary steam generator.

During the time steam is being supplied to the steam line by the auxiliary steam generator, pressure in the steam line is building up and the steam flows from the auxiliary steam generator forward toward the head end generator. This means that the point of minimum pressure in the steam line between the auxiliary steam gen-

2

erator and the head end equipment changes location. Because this minimum pressure point is variously located, the point of maximum condensate accumulation is also moved and the condensate flow is distributed to the traps on a number of cars located between steam generators. In this way it is possible for the existing steam traps to accommodate the increased condensate flow. There is no increase in the volume of steam being supplied by the head end equipment. It will be seen that the system of this invention is not subject to the problems which prevented the adoption of the previously known proposals mentioned above.

The invention will be described herein having reference to the accompanying drawing in which the system is shown in schematic form.

Reference numeral 11 indicates the steam line which extends through the train from one end to the other, the independent sections being connected serially by flexible connectors 12 between cars. Each car is provided with a condensate trap 13. Reference numeral 14 indicates the normally charged brake pipe of the conventional pneumatic brake system. This brake pipe 14 is made up of sections serially connected by means of flexible hose 15 between successive cars. Air is supplied to the brake pipe 14 through an engineer's brake valve 16. The main steam generator which supplies steam to the head end of the steam line 11 is indicated at 17. This generator may consist of more than one steam generating unit. The number of units used is selected in accordance with the weather conditions to be encountered during the trip of

As shown in the drawing, an auxiliary steam generator 18 is provided and is arranged to supply steam to the rear end of the steam line 11 under conditions to be described. Reference numeral 19 indicates a pressure actuated means which controls switches 21 and 22. The pressure motor of this switch 19 is connected to the steam line 11 as shown. A pressure actuated motor 23 operates switch 24. This motor 23 is connected to the brake pipe as shown. Connected in series circuit with the switches 21 and 24 is a switch 25 which is operated by a thermostat T sensitive to outdoor temperature. Also connected in series with these switches is an engine control panel generally indicated at 26 and a battery 27.

The auxiliary steam generator 18 is provided with a motor-driven fuel pump 28 and a motor-driven air compressor 29 by which fuel and air are supplied to the burner schematically indicated at 31. Current is supplied to drive the fuel pump and the air compressor by an alternator 32 which is in turn driven by diesel engine 33 when the latter is in operation. The starter for the diesel engine is indicated at 34. The control circuit also includes timers 35 and 36. The auxiliary steam generator's output line 37 is selectively connected to atmosphere through valve 38 or to the train steam line through valve 39. These valves 38 and 39 are operated in response to the pressure in the steam generator and valve 38 is normally open.

Control and operation of the main steam generator 17 are conventional and no description is required. The diesel engine 33 is normally stopped and its operation is commenced only when all three switches 21, 24, and 25 are closed. The switch 24 is normally closed whenever the brake pipe 14 is charged as it will be during operation of the train. A suitable pressure to cause closure of this switch is about 40 p.s.i.. The switch 25 controlled by the thermostat T will close only when the ambient temperature falls below 40° F. The switch 21 will close only when the pressure at the rear end of the train falls below 100 p.s.i. When all three switches are closed, a relay in the engine control 26 will energize the starter 34 to start the diesel engine 33. This will cause operation of the alternator to supply current

to the fuel pump and to the air compressor and start the operation of the auxiliary steam generator 18. During initial heating of the steam generator, the steam is vented to atmosphere through valve 38. The valve 38 will, by reason of its internal flow resistance, cause a back pressure to develop in the steam generator 18. When the steam pressure reaches 50 p.s.i., the valve 38 closes and the valve 39 opens, thus connecting the auxiliary steam generator 18 to the steam line 11. Continued operation of the auxiliary steam generator will cause steam line pressure to rise until it reaches 150 pounds at which time the switch 22 will open. Opening of this switch causes the timer 35 to close valve 41 and to commence timing. Unless the switch 22 recloses within a predetermined interval of time, about 12 minutes, this timer will cause the second timer 36 to commence operation. Switch 22 will reclose only if steam line pressure falls below 100 p.s.i. The second timer 36 controls a water fill valve and during its operation the auxiliary steam generator is refilled. After 4½ minutes, the timer 36 will complete its cycle and the diesel engine will be stopped and the auxiliary steam generator will shut down. If steam line pressure falls below 100 p.s.i. before the timer 35 completes its cycle, it will be reset to zero and will start to run again when steam line pressure reaches 150 p.s.i.

Typically, the head end steam generators are operated to supply steam at approximately 250 p.s.i. This steam is used for other purposes than heating the cars in the train, the principal secondary use being use in the galley of the dining car in steam tables and the like. These secondary steam users impose a variable load and hence the steam available for heating at any given time is variable. The steam pressure in the steam line becomes progressively lower as the distance from the steam generator becomes greater. This pressure gradient is commonly known as taper. The pressure of steam supplied to the train line by the auxiliary steam generator will also exhibit taper. Because the two steam generators are operated at different pressures, the gradients of the pressure drop from the two steam generators are different. This difference in gradient contributes to the change in location of the point where the two steam flows meet when both the head end and the auxiliary steam generators are operating. Observation indicates that the point of intersection moves through a greater distance along the train line when the auxiliary steam generator is operated at a pressure lower than the operating pressure of the head end steam generator. The shift in location of the point of intersection of the two steam flows is also augmented by the fact that operation of the auxiliary steam generator is cyclic. This means that the point of intersection moves forward through the train when the auxiliary steam generator is first put into operation and moves backward through the train when the auxiliary steam generator shuts down. The movement of this point of intersection of the steam flows is critical to the practical operation of the heating system of the present invention. Without this movement the condensate traps would be too small to accommodate the additional condensate load imposed on them by the addition of the auxiliary steam generator. It would not be feasible for a railroad to reequip all of its passenger cars with larger condensate traps because the expense would be prohibitive. According to the present invention, it is possible to operate longer trains under severe weather conditions and still maintain a comfortable heat in the cars, without modifying the steam distribution system in any way.

There are various secondary and manual controls on the auxiliary steam generator which have not been described, since they are, in the main, conventional, there seems no need to include a detailed description of them.

The practice of the invention is not limited to the use of the specific equipment shown in the drawing and

the scope of the present invention is intended to be measured by the appended claims.

What is claimed is:

1. In a railroad train having a steam line extending therethrough, said steam line having a plurality of condensate traps connected therewith, and main steam generating means connected to supply steam to said steam line the method of supplying steam from an auxiliary steam generator to the steam line at a point remote from the main steam generating means which method consists in admitting steam from the auxiliary generator to the steam line at said remote point when the steam pressure in the line at that point falls below a first predetermined value; and terminating the supply of steam from the auxiliary generator after pressure in the steam line reaches a second predetermined value higher than the first, whereby the point of lowest pressure in the steam line is caused to move back and forth from said remote point so that condensate is distributed to a plurality of said traps for disposal.
2. The method defined in claim 1 in which said second predetermined value is less than the pressure of steam generated by the main steam generating means.
3. In a railroad train having a steam line extending therethrough and main steam generating means connected to supply steam to said train line, the method of supplying steam from a normally inactive auxiliary steam generator to the steam line at a point remote from the main steam generating means which method consists of commencing operation of the auxiliary steam generator when the pressure in the line at said point falls below a first predetermined value; establishing flow from said auxiliary steam generator to the steam line when pressure in that steam generator reaches a predetermined level; terminating flow from said auxiliary steam generator to the steam line when pressure in the steam line exceeds a second predetermined value higher than the first; recommencing the flow of steam from the auxiliary steam generator to the steam line if, within a predetermined interval of time, the pressure in the steam line falls below said first value; and shutting down said auxiliary steam generator if the pressure in the steam line remains higher than said first predetermined value throughout said predetermined time interval after the termination of flow from said auxiliary steam generator.
4. In a heating system for the cars of a railroad train of the type in which said system includes main steam generating means, a steam line extending through said train, a plurality of condensate traps connected with said steam line, and means connecting said generating means to supply steam to said line, the improvement which comprises an auxiliary steam generator; conduit means connecting said auxiliary steam generator with said steam line at a point remote from the connecting means from the main steam generating means; and pressure-responsive valve means controlling flow through said conduit means, said valve being open when steam line pressure at said point falls below a first predetermined value and being closed when steam line pressure at said point rises above a second predetermined value higher than the first value, whereby the point of lowest pressure in the steam line is caused to move back and forth from said remote point so that condensate is distributed to a plurality of said traps for disposal.
5. In a heating system for cars of a railroad train of the type in which said system includes main steam generating means, a steam line extending through said train, and means connecting said generating means to said line, the improvement which comprises a normally inactive auxiliary steam generator; conduit means connecting said auxiliary steam generator with said steam line at a point remote from the connecting means from the main steam generating means; normally closed valve means in said conduit means; starting means for said auxiliary steam generator responsive to pressure in said steam line and

effective to put said auxiliary steam generator in operation when the pressure in the steam line at said point falls below a first predetermined value; means responsive to pressure in said auxiliary steam generator and operatively connected with said normally closed valve means to open said valve means when pressure in said auxiliary steam generator rises above a predetermined level; switch means connected to be closed when pressure in said steam line at said point reaches a second predetermined value higher than the first; timing means rendered effective by closure 10 of said switch means; means effective to re-open said switch means if pressure in the steam line falls below said first predetermined value within a predetermined interval of time, and to reset said timer; and means to shut down said auxiliary steam generator if the pressure 15 in the steam line remains above said first predetermined

value throughout said predetermined time interval after closure of said switch means.
